UNITED STATES PATENT OFFICE.

CLARK E. ACHESON, OF LOS ANGELES, CALIFORNIA.

TRUMPET.

Application filed November 30, 1927. Serial No. 236,683.

My invention pertains to a trumpet and has to do with the manner of the flow of air through the various valves of the trumpet.

5 An object of my invention in a trumpet is to pass the air directly from the mouthpiece into the first valve so that this valve secures the first dash of air. It is in the first valve that about two-thirds of the playing of a trumpet is done, and it is desirable to pass the air through the first valve before it passes to the second and the third. It has been the prior practice in constructing trumpets to pass the air to the third valve 15 first, and then through the second and first.

Another object of my invention is to give a proper balance to the trumpet in the mounting of the tube leading from the mouthpiece and to the bell on opposite sides 20 of the valves, so that the trumpet does not tend to droop to one side but is easily maintained in correct playing position.

The various features of improvement of my invention above mentioned, and other details, will be apparent from the following description and drawings, in which:

Figure 1 is a side elevation of the trumpet.

Fig. 2 is a side elevation from the opposite direction.

30 Fig. 3 is a vertical cross section on the line 3—3 of Fig. 1 in the direction of the arrows, omitting the distant parts of the trumpet.

The first, second and third valves are 35 designated 11, 12 and 13, respectively, as is the common designation in the art, although strictly speaking these designate the chambers in which the valves are located. The valves are operated by the usual keys 14.

40 The air is led from the mouthpiece 15 through a first air pipe 16, which has a straight passage on one side of the valves followed by a return bend 17; then a forward extending section 18, a front return bend 19, and a rearwardly extending connection 20 to the front valve at the position indicated at 21.

There is an air passage 22 between the 45 first valve 11 and the second valve 12, and a connection 23 between the second valve 12 and the third valve 13. The outlet from the third valve is carried by the rearwardly extending pipe 24, which has a return bend 25, a forwardly extending straight section 26, a forward return bend 27, then a rear-

ward straight section 28 terminating in the bell 29.

The trumpet is provided with a U-shaped pipe 30 connected to two positions of the third valve 13; a second U-shaped pipe 31 60 connecting two positions of the second valve 12, and a third U-shaped pipe 32 connecting two positions of the first valve 11.

From the above construction it will be noted that the air pipe 16 direct from the 65 mouthpiece passes on one side of the assembly of valves, and that the pipe 28 connecting to the bell is on the opposite side of the valve assembly, these two pipes being on approximately the same elevation. 70 The pipe 18 leading from the mouthpiece is on the same side of the valve assembly as the pipe 16, but adjacent the base of such valves, and the pipe 26 leading from the 75 third valve to the bell is on the opposite side of the valve assembly from the pipe 18, the pipe 26 and the pipe 18 being on approximately the same level.

The U-shaped pipes 30 and 32 extend respectively rearwardly and forwardly from 80 the third valve 13 and the first valve 11, and are in such position that they do not unbalance the trumpet when held in the hand. The U-shaped pipe 31 from the center valve 12 is insufficient to disturb the balance. It 85 will thus be seen that the various tubes leading from the mouthpiece to the first valve are equally placed relative to the tubes from the third valve to the bell, and that these evenly balance each other and allow the 90 trumpet to be held in the hand without the strain of endeavoring to balance this.

It will be seen from my construction that the air pipe from the mouthpiece, comprising the elements 16, 17, 18, 19 and 20, give 95 a long air passage with easy curves, and that the air pipes from the third valve, comprising the elements 24, 25, 26, 27 and 28, to the bell, also have easy curves and provide a long air column. This gives my 100 trumpet an excellent quality of tone as well as allowing easy manipulation of the valves in playing the instrument.

Various changes may be made in the principles of my invention without departing 105 from the spirit thereof, as set forth in the description, drawings and claims.

I claim:

1. A trumpet having in combination three parallel valves with keys at the top, a pipe 110

leading from a mouthpiece passing across said valves on one side adjacent the top, said pipe having a return bend, the return portion passing across said valves on the same 5 side adjacent the bottom and having a return bend leading to the first valve, a connection from the first to the second and from the second to the third valves, a pipe leading from the third valve and having a first 10 turn bend with a straight portion leading forwardly across the valves adjacent the bottom on the side opposite the pipe from the mouthpiece, said pipe from the third valve having a forward bend and a straight section leading across the valves adjacent their 15 top on the same side as the lower straight portion from the third valve, said upper pipe leading to the bell.

2. A trumpet having in combination a 20 plurality of parallel valves, a pipe leading from the mouthpiece and having return

bends and being connected to one of said valves, a pipe leading from another of said valves and connected to the bell, the said pipes from the mouthpiece and to the bell 25 being evenly balanced on opposite sides of the valves.

3. A trumpet having in combination three parallel vertical valves, a horizontal pipe from a mouthpiece having a loop on one side 30 of said valves and being connected to the first valve, the loop being on one side of said valves, a pipe connected to the bell and having a loop on the other side of said valves and being connected to the third valve, the 35 said loops evenly balancing each other on opposite sides of the said valves and a connection from the first to the second and the second to the third valves.

In testimony whereof I have signed my name to this specification.

CLARK E. ACHESON.
